UNITED STATES PATENT OFFICE.

NICHOLAS CAMELO, OF ROME, NEW YORK, ASSIGNOR, BY DIRECT AND MESNE ASSIGNMENTS, OF ONE-THIRD TO IDA JANE BLISS, OF UTICA, NEW YORK, AND ONE-THIRD TO MARY L. E. JOHNSON, OF CAMDEN, NEW YORK.

SHEET-METAL PLATING OR COATING MACHINE.

Application filed August 16, 1920. Serial No. 403,889.

To all whom it may concern:

Be it known that I, NICHOLAS CAMELO, a citizen of the United States, and resident of Rome, in the county of Oneida and State of New York, have invented certain new and useful Improvements in Sheet-Metal Plating or Coating Machines, of which the following is a specification.

My invention relates to machines for rapidly and uniformly coating sheet or plate metals or alloys with a film or layer of coating metal or alloy, and it consists in improved constructions, combinations and arrangements of parts operated automatically by the plates during their passage through the machine, to first clean them of foreign matter with an acid solution which also acts as a flux; to then apply thereto and wipe out to uniform thickness and burnish a film or layer of coating metal or alloy; to subsequently scrape or trim the edges of the coated sheets, and finally to eject them from the machine.

The accompanying drawings and description form a disclosure of my invention as best known to me at present, but as will be apparent to persons skilled in the art to which my invention appertains it is susceptible to various changes in form and portions and to various desirable additions without departing from its spirit or sacrificing any of its advantages. I therefore desire to have it understood that I include as having produced as new all such modifications as may be included within the scope of my appended claims.

In the drawings—

Fig. 1 is a side elevation of a machine constructed in accordance with my invention;

Fig. 2, a top plan of my improved machine;

Fig. 3, a central longitudinal section therethrough;

Fig. 4, an enlarged plan of one end of the frame carrying the metal wipers and showing the arrangement for operating said wipers;

Fig. 5, a vertical section through the parts shown in Fig. 4;

Fig. 6, an enlarged fragment of the machine showing the acid spray controlling mechanism;

Fig. 7, an end view of what is shown in Fig. 6;

Fig. 8, a plan view of what is shown in Fig. 6;

Fig. 9, an enlarged fragment of the machine showing one end of the metal reservoir and the means of controlling the ejection of metal therefrom;

Fig. 10, a plan view partly in section of a portion of what is shown in Fig. 9; and

Fig. 11, an end view of what is shown in Fig. 9.

Referring now to the drawings in detail it will be observed that my machine includes a pair of sides 10 and 11 formed of any desired material and design and suitably connected in spaced parallel relation to form a supporting frame for the parts to be described hereinafter. Preferably the upper longitudinal rails or bars 12 and 13 of the respective sides 10 and 11 are arranged at an incline so as to slope downward from what may be termed the front to the rear of the machine.

Adjacent the front end of the machine and extending transversely thereacross, between the upper side rails 12 and 13, with their upper portions disposed somewhat below the upper faces of said side rails, is a pair of feed rollers 14 and 15, and above and cooperating with these rollers, respectively, are rollers 16 and 17, which are journaled in suitable bearings carried by the side rails. A chain and sprocket connection 18 may be made between one of these rollers and a suitable source of power and certain of the rollers may be connected by gears 19 whereby they will be caused to rotate in unison.

Arranged transversely of the machine, in relative spaced parallel relation, between and connected to the upper side rails 12 and 13, and with their upper faces disposed somewhat below the upper faces of the side rails, is a series consisting of any desired number of platform sections 20, and in each of the spaces between these respective platform sections and also extending transversely of the machine, with their uppermost portions disposed substantially in the plane or slightly above the plane of the top surfaces of said platform sections are rollers 21.

Journaled in bearings carried by the side

22 rails 12 and 13 and extending transversely across the machine, above and in spaced parallel relation to each of the rollers 21, is a shaft 22, and longitudinally adjustable 5 on each of these shafts is a pair of discs 28, each pair of discs cooperating with respective rollers 21. Upon one end of each shaft 22 is mounted a sprocket 24 and, in a manner to be hereinafter described, these sprockets 10 are suitably connected with drive means whereby the several pairs of discs may be rotated, said discs in conjunction with the rollers 21, and the rollers 14, 16, 15 and 17 constituting the means for feeding the plates 15 through the machine and over the platform sections 20 upon which they are supported during their travel.

Rising from the upper faces of the respective side rails 12 and 13, preferably at points 20 in alignment with the first platform section 20, is a pair of blocks 25 and bridging these blocks is a ribbed bar 26 which extends transversely of the machine above said first platform section and in addition to forming 25 a support for parts of the acid spray mechanism now to be described in detail it also acts as a brace to lend stiffness and rigidity to the machine.

The acid spray mechanism includes a pipe 30 27 which extends transversely of the machine and projects through openings in the blocks 25, being closed at one end by a cap 28 and at its other end being extended as at 29 and connected with an acid supply 35 tank 30 located at any convenient point on or near the machine. The lower portion of pipe 27, between the side rails 12 and 13, is provided with a series of spaced openings 31 and controlling the flow of acid 40 from the pipe through these openings is a series of sleeves or collars 32 which are provided with openings 33 and adapted to be rotated to align or disalign the openings 35 therein with the openings in the pipe.

45 Brackets 34 are secured to the bar 26 and bearing portions of these brackets rotatably support a shaft 35 laterally with respect to the blocks 25. At spaced intervals on this shaft are fixed upwardly directed lever arms 50 36 and as best shown in Fig. 7 these lever arms are connected by links 37 with the respective collars 32. Partial rotation of the shaft 35 in one direction will result in a partial rotation of the collars 32 to align 55 the openings 33 and 31 and partial rotation of the shaft in an opposite direction will disalign said openings, as will be apparent.

Also fixed to the shaft 35 near one end thereof, and extending downwardly from 60 said shaft through a slot cut in the adjacent side rail, is a lever arm 38 which, near its extremity, is connected to a suitable fixed portion of the machine by a contractile coil spring 39 which acts through the lever arm 65 38, shaft 35, lever arms 36 and links 37 to

normally maintain the openings in the pipe 27 and collars 32 disaligned.

Pivoted at an intermediate point for rotation in a substantially lateral plane is a substantially L-shaped lever including arms 70 40 and 41, the former being bifurcated to receive the rounded terminal of the lever arm 38 and the latter being suitably shaped so that a portion thereof will project into the part of the sheets A during their travel 75 through the machine, as best illustrated in Figures 6 and 8. By reference to the latter figure it will thus be observed that movement of the laterally rotatable lever in one direction will move the lever arm 38 against the tension of the spring 39 in a direction to rotate the shaft 35 and through the links 37 to rotate the collars 32 to align the openings 33 and 31.

An air pump 42 is connected by a pipe 43 80 with the tank 30 whereby the acid in said tank may be forced into the pipe 27, said pump being driven in any suitable manner as by means of a belt 44 extending over a pulley on the crank shaft of the pump and 85 over a pulley 45 on one of the roller shafts, for instance, as shown, shaft of roller 17.

It is believed that the operation of the parts so far described will be apparent. However, it is as follows:—A plate to be 90 coated is fed into the machine between the pairs of rollers 14—16, 15—17 which rollers force it along over the first platform section 20. During the initial part of its movement through the machine the forward edge 100 of the plate comes in contact with the extremity of arm 41 of the laterally rotatable lever and rotates this lever until its extremity has moved out of the part of the plate which results in the collars being rotated 105 to align the openings 33 and 31 and permit the acid in the pipe 27 to be ejected in a spray over the plate, the side edge of the plate during its continued movement riding against the extremity of the arm 41 110 and maintaining the openings 33 and 31 aligned until the plate has passed entirely past the acid spray mechanism when the spring 39 will function to return the parts to normal position, disaligning the openings 115 33 and 31 and cutting off the acid spray until the forward edge of the next incoming plate contacts with the extremity of arm 41 and repeats the operation just recounted.

Immediately following the passage of the 120 plates beneath the acid spray mechanism they are subjected to a wiping process to spread the acid thoroughly over their upper surfaces which acts as a flux and cleans therefrom all foreign matter. Preferably 125 this wiping mechanism is located above the second platform section 20 and consists of a rectangular frame including side bars 46 connected at their ends by bars 47. This frame extends transversely of the machine 130

and is supported from the upper side rails 12 and 13 in any convenient manner. Bearings are provided within this frame at spaced intervals to rotatably receive a series 5 of vertically extending shafts 48, the upper portion of each of which is provided with a gear 49 meshing with the like gears of the next adjacent shafts whereby all of the shafts are driven in unison from a gear 10 50 on a vertical shaft 51 which latter receives its power from any desired source. A disc 52 is eccentrically mounted on the lower end of each shaft 48 and these discs carry brushes upon their under faces which 15 wipe the plates as they pass beneath said frame.

After being sprayed and wiped the plates are fed on through the machine by the discs 23 and rollers 21 until they arrive beneath 20 the mechanism for coating them, which mechanism is illustrated in detail in Figures 9, 10 and 11 of the drawings.

The coating mechanism, like the acid spray and wipers previously described, is 25 located over one of the platform sections 20 and consists of a tubular reservoir 53 arranged transversely of the machine and supported at its ends by brackets 54 rising from the side rails 12 and 13. The lower 30 portion of this reservoir is provided with a longitudinally extending enlargement centrally cut away to provide a longitudinal channel 55 opening into the lower face of said enlargement. Slidable in the channel 35 55 is a plurality of devices 56 and these are retained in the channel by plates 57 and 58 secured to the under face of the enlargement with their inner edges underlying the lower faces of said devices. An apertured 40 device 59 projects downward from each device 56.

A bar 60 extends transversely of the machine below, parallel to and lateral of the series of devices 56 and is mounted for reciprocation in bearing brackets 61 secured 45 to the respective ends of the reservoir. Rigidly secured to this bar is a plurality of spaced pins 62 which are respectively engaged in the apertures of the devices 59. 50 The devices 56, because of their connection with the bar 60, are movable in unison to cover or uncover a spaced series of openings 63 in the lower wall of the reservoir and in order that these openings may be 55 uncovered and covered at the proper times mechanism similar to that for controlling the ejection of acid from the pipe 27 is employed.

The mechanism referred to consists of a 60 vertically arranged lever arm 64 pivoted at its upper end to one end of the bar 60, pivoted intermediately to a bracket 65 secured to the adjacent side rails and at its lower end engaged in a bifurcated portion 65 of a horizontally rotatable lever 66 which is

also pivoted at an intermediate point and has one arm 67 thereof projecting into the path of travel of the plates to be coated. Connecting the arm 67 of lever 66 with a suitable fixed part of the machine is a contractile coil spring 68 which exerts an influence to move the parts to a position causing the devices 56 to normally maintain the openings 63 covered.

A tank 69 containing the molten coating 75 metal or alloy is connected with the reservoir 53 by a pipe 70 and through any desired instrumentality maintains a predetermined amount of molten metal or alloy in the reservoir, and in the event the metal so 80 contained becomes chilled or in order to prevent it from becoming chilled, means in the nature of nozzles 71 may be provided for directing jets of hot flame against the sides of the reservoir to heat and maintain the 85 metal therein at a uniform temperature.

The operation of the mechanism just described for supplying a coating of metal or alloy to the plates as they pass beneath the reservoir 53 is substantially identical with 90 the mode of operation of the acid spray mechanism. During its movement through the machine the forward edge of the plate to be coated contacts with and moves the extremity of the arm 67 of lever 66 until the 95 devices 56 uncover the openings 63 permitting the metal or alloy in the reservoir to flow through said openings and onto the plate passing therebeneath. A predetermined amount of movement of the plate results in 100 the extremity of arm 67 being moved out of the path of the plate after which it rides against one side edge thereof and maintains the openings 63 uncovered until the plate has passed by when the coil spring 68 acts 105 to return the parts to their normal position closing the openings 63 and in readiness to repeat the operation when the next plate moves in position to be coated.

Following their passage beneath the coating mechanism the plates are subjected to a wiping operation for uniformly spreading the coating material thereover and burnishing the same. This wiping means is very similar to the acid wiping means and consists of a rectangular frame extending transversely across the machine and supported in any suitable manner from the side rails 12 and 13 above the platform sections, said frame, as shown, including a pair of side 115 bars 72 connected at their ends by bars 73.

Carried by each of the side rails 72 is a set of spaced bearings and rotatable in each of these bearings is a vertical shaft 74 which, at its upper end, carries a gear 75. Two 125 separate series of gears and shafts are thus provided and as illustrated the several gears of the first series as well as the several gears of the second series intermesh. Preferably, however, there does not exist any inter- 130

meshing relation between the respective series of gears, but the gears of both series may be driven from a common source by a gear 76 on a vertical shaft 77 journaled in a bearing carried by one of the end bars 73. This gear 76 meshes with one of the gears 75 of each series and the shaft 77 carrying the same has fixed to its lower end a bevel gear 78 which meshes with a similar gear 79 on a short horizontal shaft 80 which is journaled in a bearing carried by one of the upper side rails and at its outer end carries a sprocket 81 which may be connected to any desired source of power and rotation of which, as is apparent, will result in uniform rotation of all the shafts 74.

A disc 82 is eccentrically mounted on the lower end of each shaft 74 and upon their lower faces these discs carry brushes which wipe the upper faces of the plates as they pass beneath the frame, the first series of brushes serving to wipe out the coating material to uniform thickness and the second series serving to complete the wiping process as well as burnish plates.

After passing beneath the wiping mechanism just described the plates are moved on by the rollers 21 and discs 23 to a mechanism for scraping and trimming their edges. This mechanism consists of a pair of shafts 83 and 84, the former extending transversely of the machine above the plane of the platform sections and the latter extending transversely of the machine below the plane of the platform sections, said shafts being relatively disposed in parallelism and preferably in substantially relative vertical alignment. One end of one of these shafts has fixed thereon a sprocket 85 and both shafts, between the side rails 12 and 13, have longitudinally adjustable thereon a pair of discs 86 having fine toothed peripheries or cutting edges. The discs of the two shafts operate in pairs and as the edges of the plates pass between them the teeth or cutting edges of the discs function to scrape and trim the edges of all surplus and inequalities in the coating material. Preferably adjustable bearings are provided for the shafts 83 and 84 so that the distance between the discs 86 may be varied, but these bearings may form the subject matter of a separate application and are therefore not shown in detail. After passing between the edge scraping and trimming discs the plates are ejected from the machine by the last set of discs 28 and roller 21.

If desired pans may be provided beneath the acid spray and coating mechanisms to receive any acid or coating material which might be delivered to the plates in excess of the amount needed, and furthermore certain of the collars 32, and devices 56 may be disconnected from their operating means and the discs 23 and 86 adjusted on their

shafts in order that plates of various widths may be coated by the machine without unnecessary waste of acid or of the coating material.

Power for rotating the various shafts of the machine may be applied in various manner, but I prefer the sprocket and chain arrangement best shown in Fig. 1 of the drawings. This arrangement consists of a pair of spaced stub shafts 87 and 88 extending laterally from one side of the frame of the machine and each carrying a sprocket 89 which sprockets are connected by a chain 90. Each of these shafts in addition carries a plurality of smaller sprockets and these latter are connected by chains 91 with the several sprockets 24. A second sprocket on one of the shafts 22 is connected by a chain 92 with the sprocket 85 on one of the edge scraping and trimming disc carrying shafts and all of the sprockets with their shafts are rotated from the shaft of roller 17 by means of a chain 93 connecting a sprocket 94 on this shaft with a sprocket on the stub shaft 87.

I claim:

1. A machine for coating sheet material comprising, means for advancing the material through the machine, and means including an element disposed laterally with respect to the material and actuated by contact with the forward edge of the same to cause application of the coating substance thereto.

2. A machine for coating sheet material comprising means for advancing the material through the machine, and means including an element disposed laterally with respect to the material and actuated thereby to cause application of the coating substance thereto.

3. A machine for coating sheet material comprising means for advancing the material through the machine, means including an element disposed laterally with respect to the material and actuated thereby to cause application of the coating substance thereto, said means operating automatically to cut off application of the coating material following advance of the material past said element.

4. A machine for coating metal sheets comprising means for advancing the material through the machine and relatively independent means for respectively applying a liquid flux and subsequently a liquid coating material to the sheets during their advance, said means being operable automatically by the sheets during their advance through the machine to initiate application of the flux and coating material and including elements constantly tending to cut off the flow of the same.

5. In a machine for coating metal sheets, means for advancing the sheets through the

machine, means for supplying a liquid flux to the advancing sheets including a supply pipe having a series of longitudinally spaced openings therein, a series of members arranged in end to end abutting relation for controlling the flow of the liquid flux through said openings, and means operable by the advancing sheets to at predetermined times move said members to uncover said openings.

6. In a machine for coating metal sheets, means for advancing the sheets through the machine, means for supplying a liquid flux to the advancing sheets including a supply pipe having a series of longitudinal spaced openings therein, a series of collars embracing said pipe and arranged in end to end abutting relation, and means operable by the advancing sheets to move said collars to uncover said openings, said means including a member and independent removable connections between said member and each collar, whereby selected connections may be removed to render related 25 collars inoperative to uncover predetermined openings upon operation of the member by the advancing sheets.

7. In a machine for coating metal sheets, means for advancing the sheets through the machine, means for supplying coating material to the advancing sheets including a reservoir having a series of openings therein, a series of devices arranged in end to end relation and movable longitudinally 30 of the reservoir for controlling the flow of coating material through said openings, means for moving said devices in unison including a member actuated by the advanc-

ing sheets, and independent removable connections between said member and said devices whereby selected connections may be removed to render related devices inoperative to uncover predetermined openings upon actuation of the member by advancing sheets.

8. A machine for coating metal sheets, comprising, in combination, acid spray means, means for wiping the acid over the sheets, metal spray means, means for wiping the metal over said sheets, and means including a pair of discs for scraping and trimming the edges of said sheets.

9. In a machine for coating metal sheets, a metal containing reservoir having an opening therein, a slidable device movable transversely of the machine for controlling the flow of metal from said reservoir through said opening, and means operated by a sheet positioned to receive metal from said reservoir for sliding said device.

10. In a machine for coating metal sheets, a metal containing reservoir having a plurality of openings therein, slidable devices for controlling the flow of metal from the reservoir through said openings, means for sliding said devices in unison, and means including a plurality of levers operated by a sheet during its advance through the machine to slide said devices.

In testimony whereof I hereunto affix my signature in the presence of two witnesses.

NICHOLAS CAMELO.
